(No Model.)

S. W. SHAW.
Combined Folding Cot and Settee.

No. 236,850.

Patented Jan. 18, 1881.

UNITED STATES PATENT OFFICE.

S. WHEELER SHAW, OF CHICAGO, ILLINOIS.

COMBINED FOLDING COT AND SETTEE.

SPECIFICATION forming part of Letters Patent No. 236,850, dated January 18, 1881.

Application filed August 27, 1880. (No model.)

To all whom it may concern:

Be it known that I, S. WHEELER SHAW, of Chicago, in the county of Cook and State of Illinois, have invented certain new and useful Improvements in Combined Folding Cot and Settee, of which the following is a specification.

My invention relates to improvements in flexible-bottomed folding settees, which may be converted into a cot or couch when desired; and the same consists in the arrangement and combination of the devices herein described, whereby the folding settee may be used either as a couch or settee, or be folded up into a compact form when not in use, if desired.

In the accompanying drawings, which form part of this specification, Figure 1 is a perspective view of a device embodying my invention when in position to be used as a settee, and Fig. 2 is an end view of the same when it is extended to be used as a couch or cot.

In said drawings similar letters of reference refer to like parts wherever used.

In said drawings, A represents the flexible bottom of the settee, made of any suitable cloth or material, one edge of which is secured to the rail or frame-piece B, extending between the folding legs C and C', and its other edge is secured to the railing or frame-piece D, which extends between the folding arms E and E', pivoted at e and e' to the legs F and F'. The legs F and F' are curved and extended up to form the back of the settee. When the folding arms E and E' are extended to form a couch, as shown in Fig. 2, the same are secured in such position by means of the hooks H, attached to said arms, and the staples or brackets h, attached to the legs F and F'; and when the same are folded to form a settee, as shown in Fig. 1, they are held in position by means of the pins h', which pass through holes designed for the purpose in the folding arms E and E' and legs F and F'.

G G are braces extending across from folding legs C and C' and legs F and F', and g is a back strip secured to the folding arms E and E', which, together with the strip D, forms the back or part of the back of the settee.

I is a flexible back, one edge of which is se-

cured to the top back strip, J, and the other edge of which is secured to the movable back strip, J'. This movable back strip, J', is secured in position for use, as shown in Fig. 1, by means of the pins K, and the legs F and F' are also provided with notches k for the same purpose. This flexible back may be folded up, as shown in Fig. 2, and secured in such position by means of the string k'. I sometimes make my combined folding cot and settee without this part of the back, which is secured, as stated, to the legs F and F', in which case the folding arms E and E' and strips D and g constitute the back of the settee, and the legs F and F' are not extended above the arms E and E'; but I prefer to construct the same as shown in the drawings.

L is a flexible arm, made of cloth or like material, secured at each end to the right-angled arms l and l', the former of which is attached by suitable bolts or screws to the folding leg C, and the latter to the leg F. This flexible folding arm serves not only as an arm to the settee, but also as a pillow for the cot. A like arm may be provided at the other end of the settee, if desired.

When not in use the folding settee or cot may be folded up into a compact shape, like an ordinary camp-chair.

I claim—

A folding settee composed of folding cross-legs intersecting each other below the seat, as shown, and pivoted at such intersection, two of them, F and F', extending upward above the seat and provided with cross-bar J, the hinged back frame, suitable devices for detachably securing the hinged back frame to the extensions of the cross-legs in both positions, front and back rails, a cover for the bottom and hinged portion, made in one piece, of cloth or other suitable material, and an arm, serving also as a head-rest, composed of cloth mounted upon and stretched between uprights upon the legs or rails at front and back, substantially as set forth.

S. WHEELER SHAW.
